UNITED STATES PATENT OFFICE.

FRIEDRICH ERDMANN RICHTER, OF LEIPSIC, GERMANY.

MANGLE.

SPECIFICATION forming part of Letters Patent No. 594,430, dated November 30, 1897.

Application filed March 20, 1896. Serial No. 584,186. (No model.) Patented in Germany July 10, 1895, No. 86,624; in France November 19, 1895, No. 251,818; in England November 29, 1895, No. 22,903; in Switzerland February 18, 1896, No. 12,004, and in Austria April 3, 1896, No. 46/1,297.

To all whom it may concern:

Be it known that I, FRIEDRICH ERDMANN RICHTER, model-maker, of 36 Merseburgerstrasse, Leipsic-Plagwitz, in the Kingdom of 5 Saxony, German Empire, have invented new and useful Improvements in Mangles, (for which I have obtained a patent in Germany, No. 86,624, bearing date July 10, 1895; in France, No. 251,818, bearing date November 10, 1895; in Great Britain, No. 22,903, bearing date November 29, 1895; in Switzerland, No. 12,004, bearing date February 18, 1896, and in Austria, No. 46/1,297, bearing date 15 April 3, 1896,) of which the following is a specification.

My invention relates to a mangling-machine by means of which two parties may 20 mangle independently of each other, the machine being used in common and driven either by hand or by machine power.

In the accompanying drawings a mangling-machine is represented.

Figure 1 is a front view of the same, the left-hand side showing the mangle in operation, while on the right-hand side the lowest set of rollers is represented out of action and the upper set has been omitted. Fig. 2 is a side view of the same.

The improved mangling-machine comprises, 30 essentially, two standards, consisting each of two plates *a a'* and serving for the reception of the drum *b*. Upon the shaft *c* of the drum *b* a toothed wheel *d* is rigidly secured, which is rotated together with the drum by means 35 of toothed wheels *d' d'' d'''*, pivotally arranged between the plates *a a'* of one of the standards. The toothed wheel *d'''* is mounted upon the shaft *e* of the fly-wheel *e'*, and the toothed wheels *d'* and *d''* are fixed upon an intermediate shaft. The toothed wheel *d'* meshes with the toothed wheel *d*, and the toothed wheel *d''* meshes with the toothed wheel *d'''*. The operation takes place either by means of a handle *e''*, directly fixed on the fly-wheel *e'*, 45 or by means of a pulley especially arranged.

On each of the two sides of the drum *b* are arranged two pairs of rollers *f f'* and *g g'*, one of which is placed above the other and which can be used at the same time, the arrangement being, moreover, such that each single

pair of rollers can be disengaged and that one pair, two pairs, three pairs, &c., may be used for the working, according to requirements. The rollers *f* and *g* serve for the reception of the washing to be mangled, which 55 has to be laid with hand over the entire length of the same. The rollers themselves are supported in the arms *h* in such a manner as to be removed easily out of their bearings. For this purpose the arms *h* have at 60 the upper ends slots which open to the upper side and serve for bearings of the rollers. The arms *h* are adapted to turn about bolts *i*, fixed to the plates *a*, so that an engagement and disengagement of the rollers mounted in 65 these arms with the drum can be executed. In order to prevent the arms with the rollers moving too far in disengagement, stop-bolts 70 *k* are arranged which retain the arms after disengagement in their inoperative position. 75 The pressing-rollers *f'* and *g'* are mounted on arms *m*, pivotally arranged upon bolts *l*, and serve to press the rollers *f* and *g* against the drum *b* in order to effect in this way the smoothing of the washing. When disengaged, the arms *m* rest against the stop-bolts *k'*, so that a further outward movement of the pressing-roller is prevented.

In order to press the pressing-rollers *f'* and *g'* against the rollers *f* and *g* and the latter 80 against the drum *b*, there are arranged rollers *n*, which are pressed against the pressing-rollers *f'* and *g'* by means of double lever-arms *o*, to the longer shank of which a weight *p* is attached. By adjusting the weight *p* on the 85 lever-arm the pressure required for smoothing the washing can be suitably regulated. Each of the rollers *n* is mounted in a rod *q*, swinging round the point *r* and connected at its shorter shank by means of a link-piece 90 *s* with the disengaging lever *t*. The double lever-arm *o*, which is adapted to swing round the point *o'*, catches with its shorter shank suitably bent behind the suspending arm of the mangle-rod *q*, and presses thereby the 95 roller *n* against the pressing-roller *f'* or *g'*, from which the pressure is transferred to the roller *f* or *g* and to the drum *b*. The disengaging lever *t* is pivotally mounted round the bolt *t'* and bears with its shorter arm upon the 100

lower side of the longer shank of the lever *o*, carrying the weight *p*. From this arrangement results that when the lever *t* is brought into the position shown in Fig. 1 on the right-hand side the lever *o* raises with the weight, whereby the shorter arm of the lever *o* sets free the mangle-rod *q* with the roller attached to it. Because the mangle-rod *q* is connected with the longer shank of the disengaging lever *t* by means of the link-piece *s*, the mangle-rod *q* is turned round the point *r* and the roller *n* releases the pressing-roller.

When one pair of rollers is disengaged, the roller *f* or *g* is removed and wound about with the washing to be smoothed, after which the roller is put back into the bearings of the arms *h*. Now the roller wound about with washing is pressed against the drum *b* by means of lifting the pressing-roller, after which the levers *t*, being arranged on both sides, are lifted, and effect thereby a pressing of the rollers *n* against the pressing-roller. The drum *b* is constantly rotating, and because the pressing-roller is pressing the roller wound about with washing against the drum, the roller wound about in consequence of friction is also rotated and effects thereby the smoothing of the washing. After sufficient mangling the roller wound about is released by means of the disengaging levers *t* and may be wound about again after the smoothed washing has been taken off. The drum *b* remains constantly in movement be-

cause one pair of rollers can be provided always with washing to be smoothed. 35

Having now described my invention, what I claim, and desire to secure by Letters Patent, is—

In a mangling-machine the combination of a rotary drum supported between two standards, with two rollers for the reception of the washing to be smoothed, arranged on each side of the said drum and supported by pivotal levers, rollers also arranged on each side of the drum and supported by pivotal levers 40 and pressing upon the rollers carrying the washing, rolls also arranged on each side of the drum and supported by pivotal levers and pressing upon the said pressing-rollers, weighted levers the shorter arm of which 45 presses against the longer arm of the levers carrying the said rolls, and levers the longer arm of which forms a handle and the shorter acts upon the longer arm of the said weighted levers and being connected by means of 50 link-pieces with the shorter arm of the levers carrying the said rolls; as and for the purpose set forth.

In testimony whereof I have signed my name to this specification in the presence of 60 two subscribing witnesses.

FRIEDRICH ERDMANN RICHTER.
